UNITED STATES PATENT OFFICE.

WALTER A. GOERTZ, OF EAST ORANGE, NEW JERSEY, ASSIGNOR TO AUGUST GOERTZ & CO., INC., OF NEWARK, NEW JERSEY, A CORPORATION OF NEW JERSEY.

VANITY CASE.

Application filed March 3, 1928. Serial No. 258,737.

This invention relates to improvements in cosmetic boxes or vanity cases; and the invention has reference, more particularly, to a novel means for assembling and retaining a 5 mirror, compact or other insert in connection with a box section.

This invention has for its principal object to provide a simple, inexpensive and easily and quickly assembled construction whereby 10 a retaining frame for a mirror, compact or other insert may be strongly interlocked with a box section; and to this end the box section is provided with an in-curved annular bead or rim and the retaining frame is provided with 15 radially projecting peripheral lugs adapted to be sprung beneath the bead or internal rim of said box section, all as hereinafter more particularly described.

Another object of this invention is to provide 20 a means for holding the assembled retaining frame against rotatable displacement or shifting relative to the box section with which it is assembled with attendant advantages also hereinafter set forth.

25 The invention is clearly illustrated in the accompanying drawings, in which:—

Figure 1 is a top view of a cosmetic body or vanity case embodying the principles of this invention; Figure 2 is a plan view of said 30 box or case opened; Figure 3 is a plan view of the retaining frame detached from the box or case; Figure 4 is a fragmentary sectional view, on an enlarged scale, taken on line 4—4 in Figure 2; Figure 5 is a fragmentary sectional view on line 5—5 in Figure 2, also on an enlarged scale; and Figure 6 is a fragmentary perspective view of the hinge knuckle of the box-section showing features relating to the retaining frame holding means.

40 Figure 7 is a plan view of a modified construction of box or case, and Figure 8 is in part a side elevation and in part vertical section through the same on line 8—8.

Similar characters of reference are employed 45 in all of the hereinabove described views to indicate corresponding parts.

Illustrative of the principles of this invention I have shown, in Figures 1 to 6 inclusive, a simple form of cosmetic box or case, comprising 50 a pair of hingedly connected sections so arranged that one of said sections constitutes a cover 10 and the other a body 11 upon which the cover closes. In boxes or cases of this character, which are designed to serve 55 the purposes of cosmetic carriers or vanity

cases, it is desired to attach a mirror in connection therewith, and the invention in part relates to a novel construction of mirror retaining frame which may be firmly and securely assembled with the cover section of the 60 box or case, in interlocked relation thereto, without necessity of using solder or detachable fastening means of any kind; said retaining frame being adapted to retain a mirror 12 in attached relation to the inner side 65 or face of said cover section 10. Said cover section 10 is provided at one point of its periphery with transversely disposed tubular hinge knuckle 13, which may be integrally formed from a tongue of metal extending 70 from the body of said section, or which may be formed as a separate element soldered to the cover section. Said cover section 10 is provided around its margin, and extending 75 from one end of the hinge knuckle around the periphery to the opposite end of the latter, with an in-curved annular bead or flange 14 to provide a shallow internal channel or groove 15. The reference character 16 indicates 80 a retaining frame or annulus having at its internal circumferential an outwardly offset keeper flange 17 to provide a holding seat for retaining the mirror 12 backed against the inside surface of said cover section. The diameter of the external circumference of said 85 retaining frame or annulus is less than the internal diameter of the bear or flange 14, so that the retaining frame or annulus may be overlaid upon the inside surface of said cover section 10 around the mirror 12, with the marginal portions of the latter engaged and held 90 by the off-set keeper flange 17. The means for interlocking the retaining frame with the cover section in fixed assembled relation thereto, and in holding engagement with the mirror 95 12, comprises a plurality of circumferentially spaced radially projecting lugs or tongues 18 extending from the external circumference of said retaining frame. In assembling the retaining frame with the cover section 10 the extremities of the lugs or tongues 18 are sprung past the free edge of and beneath the in-curved annular bead or flange 14 and into the channel or groove 15, thus locking the retaining frame in attached 105 relation to the cover section.

While I have described the use of the retaining frame when assembled with the cover section as a means for retaining a mirror in affixed relation to the inside surface of said 110

cover section, it will be understood that devices other than mirrors may be thus secured within the cover section.

It may be desirable under some circumstances to provide positive means for preventing rotatable displacement or shifting of the retaining frame. For example, vanity cases are frequently given a fanciful name which is suitably inscribed on the retaining frame 10 (as shown in Figure 2); or the retaining frame may be given a surface decoration or design, the symmetrical relation of which with respect to the cover section it is desired to maintain; in such and similar cases the means to hold the retaining frame against shifting or displacement is of advantage. In the present invention, the means for holding the retaining frame against shifting, comprises a cut-away portion or notch 19 formed 20 on the inner side of the hinge knuckle 13. The retaining frame 16 is provided at a predetermined point in its external periphery with an outwardly extending upwardly inclined positioning tongue 20 the free end of 25 which is extended into said notch 19 of the hinge knuckle 13 so as to be embraced thereby, and so as to overlie the pintle P of the box hinge, all whereby the frame is secured against turning in the cover section. 30 The body 11 of the box or case is provided in connection with its side walls with spaced hinge knuckles 22 between and into alignment with which the hinge knuckle 13 of the cover section 10 may be disposed so that the hinge 35 pintle P may be passed therethrough to pivotally interconnect the body and cover sections together.

Referring now to Figures 7 and 8 of the drawings, I have shown therein a modified construction of cover section for vanity case 40 with which the novel retaining frame may be assembled to serve as a means to retain design inserts within an opening in the cover section, and also hold a mirror within the latter if desired. In this construction the cover section 10 is provided in its wall with an opening 23 of a size or diameter less than its overall diameter. The reference character 24 indicates a design insert having a portion to fit 45 into and be exteriorly exposed in or through said opening, and having a circumferential flange or marginal portion 25 to abut the inside surface of the cover section. The cover section is provided with the in-curved annular bead or flange 14 the same as above described. The retaining frame 16 is overlaid upon the flange or marginal portions 25 of the design insert 24, and its peripheral lugs or tongues 18 are sprung beneath the cover bead or flange 14 thus securely interlocking said retaining frame to the cover and in holding relation to the design insert 24, as will be understood from an inspection of Figure 7. If desired the interior circumference of the retaining frame may be provided with the outwardly 55

off-set internal keeper flange 17 to retain and hold a mirror on the inside of the modified cover section if desired.

In the constructions of cosmetic boxes or vanity cases above described, the in-curved annular bead or flange 14 of the cover section 10 is arranged to telescope over the free marginal portions of the side walls of the body section 11, when said cover section 10 is disposed in closed relation to said body section 11. This is shown, more especially, in Figure 8 of the drawings.

Having thus described my invention, I claim:

1. In a vanity case having cooperating sections, means for assembling and retaining an inserted member in connection with a section thereof, comprising an in-curved peripheral rim on said section, and an inserted member retaining frame arranged within the internal limits of said rim, said retaining frame having outwardly extending lugs spaced about its outer periphery, said lugs being sprung beneath said in-curved rim of said section.

2. In a vanity case having a body section and a cover section hingedly connected together, means for assembling and retaining an inserted member in connection with said cover section, comprising an in-curved peripheral rim on said cover section, and an inserted member retaining frame arranged within the internal limits of said rim, said retaining frame having radially extending lugs spaced about its outer periphery and sprung beneath said in-curved rim of said cover-section, and said in-curved rim of said cover-section being adapted to telescopically engage over the free marginal portions of the side walls of said body-section when said sections are closed together.

3. In combination with a section of a vanity case, an in-curved peripheral rim on said section to provide an underlying groove, an inserted member engaged with the inside face of said section, a retaining frame to hold said inserted member, and means to interlock said retaining frame with said section, comprising lugs integral with said retaining frame and projecting from the outer margins thereof, said lugs being sprung beneath said section rim and into said groove underlying the same.

4. In a vanity case, a body section and a cover section, said sections having cooperatively aligned hinge knuckles, a hinge pintle extending through said knuckles to pivotally interconnect said sections, means for assembling and retaining an inserted member engaged with the inside face of said cover section, comprising an in-curved peripheral rim on said cover section to provide an underlying groove, a retaining frame to hold said inserted member, lugs integral with said retaining frame and projecting from the outer margins thereof, said lugs being sprung be-

neath said rim and into said groove underlying the same, and means to hold said retaining frame against shifting comprising a tongue extended therefrom, and a cut-away

5 portion in one of said hinge knuckles to receive and embrace said tongue.

5. In combination with a section of a vanity case, an in-curved peripheral rim on said section to provide an underlying groove, a
10 hinge knuckle projecting from the periphery of said section, said rim terminating at opposite sides of said hinge knuckle, an inserted member engaged with the inside face of said section, a retaining frame to hold said inserted member, means to interlock said retaining frame with said section, comprising lugs integral with said retaining frame and projecting from the outer margins thereof, said lugs being sprung beneath said section
15 20 rim and into said groove underlying the same, and means to hold said retaining frame

against shifting comprising a tongue extended therefrom, said hinge knuckle having a notch in its inwardly facing side to receive and embrace said tongue.

25

6. In combination with the cover section of a vanity case a mirror superimposed on the inside face thereof, means to hold said mirror in place, comprising a retaining annulus having an off-set keeper flange at its internal circumference to engage the marginal portions of said mirror, and means to interlock said retaining annulus with said cover section, comprising an in-turned peripheral rim on said cover section, and lugs extending from the external circumference of said annulus and sprung beneath said cover section rim.

In testimony that I claim the invention set forth above I have hereunto set my hand
40 this 2nd day of March, 1928.

WALTER A. GOERTZ.
